UNITED STATES PATENT OFFICE.

AMOS EBY, OF LEAMAN PLACE, PENNSYLVANIA.

DEFLECTOR.

SPECIFICATION forming part of Letters Patent No. 574,024, dated December 29, 1896.

Application filed March 27, 1896. Serial No. 585,054. (No model.)

To all whom it may concern:

Be it known that I, AMOS EBY, a citizen of the United States, residing at Leaman Place, in the county of Lancaster, State of Pennsylvania, have invented certain Improvements in Deflectors, of which the following is a specification.

This invention relates to improvements in that class of deflectors designed for throwing out toward the center of an apartment the hot air entering the same through a wall-register; and the object of the improvements is to prevent the hot air from rising directly toward the ceiling after escaping from the register and to direct it to and out over the floor of the apartment, so as to diffuse the hot air through the same directly from the register.

The invention consists in the construction and combination of the various parts, as hereinafter fully described and then pointed out in the claims.

In the accompanying drawings, which form a part of this specification, Figure 1 is a perspective front view of a deflector embodying my invention; Fig. 2, a vertical longitudinal section thereof, showing the deflector attached to the front face of a register; Fig. 3, a similar section of the deflector detached, showing a modification of the device for adjusting the inclination of the deflector-plate; and Fig. 4 a top view of the deflector detached.

Similar letters indicate like parts throughout the several views.

Referring to the details of the drawings, A indicates a wall-register, and B the deflector, constructed, preferably, of sheet metal.

B' is the horizontal top plate of the deflector, B² vertical side plates or cheeks formed with or connected to the top plate at their upper ends, and b a wire connecting the lower inner corners of the cheeks to maintain the lower ends thereof in their proper relative positions. This wire preferably extends up the outer sides of the inner edges of the cheeks, being held in loops b', formed by turning over the edges of said cheeks. Immediately beneath the inner edge of top plate B' a hinge-rod d is supported in the cheeks, and on rod d is hinged a deflector-plate D, which is of the full width of the space between the cheeks. The deflector-plate slopes down-

ward and outward from the hinge-rod, as illustrated, and the angle of inclination is regulated by a rack-bar E, pivotally connected at 55 its lower end with the vibrating edge of the deflector-plate and having its upper end passing through a slot e in the top plate B', said rack-bar being held in an adjusted position by the engagement of one of the teeth e' 60 thereon with an edge of slot e. The upper end e² of said rack-bar is turned over to form a handhold.

Instead of rack-bar E a chain F may be used, the links of which are engaged over a 65 hook f, as shown in Fig. 3, those above the hook passing through slot e. The hinge-rod is so located that the upper end of the deflector-plate works against or in contact with top plate B', so as to prevent the escape of 70 any material part of the hot air from the register through the joint between said top plate and deflector-plate.

The top plate and the side plates need not be of the contours shown, but may be constructed of any pleasing design suitable for 75 the purpose.

G represents inwardly-projecting arms on the inner faces of cheeks B², and on the ends of said arms are rearwardly-extending hooks g, 80 adapted to take over the bars, a, of the wall-register, as illustrated in Fig. 2.

The deflector is of such dimension that the top and sides embrace all the outlet-openings of the register, the inner edges of the top and 85 sides of the deflector being constructed to set up flush against the face of the rim of the register. The hot air pouring through the register, instead of rising directly to the ceiling of the apartment, as it ordinarily does, 90 strikes deflector-plate D, and is by it deflected toward and out over the floor, as shown by arrows r, Fig. 2.

This deflector tends to spread the hot air directly out into the room as it is discharged 95 from the register, and permits the feet and person to be warmed, instead of allowing the hot air to rise at once and strike against the face.

I do not limit myself to any particular mode of securing the deflector to or in front of the register; neither do I restrict myself to the particular manner of hinging the deflector-plate herein shown and described.

Having thus described my invention, what

I claim as new, and desire to secure by Letters Patent, is—

1. The combination, with a register, of vertical side plates or cheeks, a deflector-plate 5 hinged between the inner edges of the cheeks, the free edge of said deflector-plate being adapted to be adjusted vertically between said cheeks, and means for securing the free edge of said deflector-plate in an adjusted position, for the purpose specified.
2. The combination, with a register, of a deflector comprising a horizontal top plate, vertical side plates or cheeks, hooks constructed to engage the register, a deflector-

plate having its upper edge hinged between 15 the inner edges of the cheeks and adjacent to the top plate, and a rack-bar having one end pivoted to the vibrating end of the deflector-plate and the other end passing through a slot in the top plate, the rack on said bar 20 being constructed to engage an edge of said slot, substantially as and for the purpose specified.

AMOS EBY.
